UNITED STATES PATENT OFFICE.

THOMAS DAVIS, OF SCRANTON, PENNSYLVANIA.

DESIGN FOR A BOTTLE.

SPECIFICATION forming part of Design No. 13,736, dated March 20, 1883.

Application filed December 20, 1882. Term of patent 14 years.

To all whom it may concern:

Be it known that I, THOMAS DAVIS, of Scranton, in the county of Lackawanna and State of Pennsylvania, have invented a certain new and Improved Design for Bottles, of which the following is a full and exact description and specification.

Referring to the accompanying drawings, Figure 1 represents a side elevation of my invention; Fig. 2, a bottom plan view of the same.

My design consists in making the bottle of triangular form in cross-section, with flat sides tapering inward from the bottom to a point, *b*, and in curving the bottle from the point *b* to the base of the neck at *c*, and forming the neck of cylindrical form, extending from point *c* to

point *d*, and curving the bottle outward from the point *d* to the mouth-rim *e*, as shown.

This design is very attractive, and serves to distinguish the bottle from others known to the trade.

I claim as my invention—

The bottle herein described, triangular in cross-section, with sides tapering from the bottom to the point *b*, thence extending in the form of a straight cylindrical neck to the point *d*, and thence curving outward to the mouth-rim *e*, substantially as described.

THOMAS DAVIS.
